Application November 27, 1936, Serial No. 66,173
In Great Britain November 10, 1936

Term of patent 14 years

To all whom it may concern:

Be it known that I, James McQuitty, a subject of the United Kingdom of Great Britain, and a resident of 89 Princetown Road, Bangor, County Down, Northern Ireland, have invented a new, original, and ornamental Design for a Deck of Playing Cards, of which the following is a specification, reference being had to the accompanying drawing, forming part thereof.

The drawing illustrates a face view of each of the court cards, an ace card and a number card

showing my new design. The remaining number cards of the deck follow the design of the ten card with the exception that the respective numbers of each card are used where the word and numbers 10 appear in the card illustrated. The backs of all the cards are conventional.

I claim:—

The ornamental design for a deck of playing cards as shown, and described.

JAMES MCQUITTY.
